UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed December 28, 1923. Serial No. 683,142.

To all whom it may concern:

Be it known that I, RUSSELL H. WILHELM, a citizen of the United States, and resident of Easton, county of Northampton, State of Pennsylvania, have invented 5 a certain Steel Retainer, of which the following is a specification accompanied by drawings.

This invention relates to drill steel retainers for rock drills, but more particularly to that type of retainer in which a yoke embraces the drill steel and is suitably held or clamped in position upon the front head of the machine.

15 Retainers for the collared working implement of fluid actuated machines must be sturdy and rugged to withstand the vibration set up in the operation of the machine and the rough usage to which they are subjected. In the event of breakage, they must be so constructed that broken parts may be readily replaced in order that the time required for repairs be reduced to a minimum. It is also desirable to hold the retainer in 20 operative position to prevent the vibration of the machine from moving the retainer away from the working implement, as well as to enable the retainer to be held in inoperative position when it is desired to remove the working implement from the machine.

One object of this invention is to enable a retainer for the collared working implement of a fluid actuated percussive machine 35 to be securely held in operative retaining position or held in inoperative position away from the working implement.

Another object of the invention is to produce a retainer for a collared working implement of a fluid actuated percussive machine which is simple in its construction, is composed of but few parts, is cheap to manufacture and is capable of withstanding the hardest kind of usage.

45 Further objects of the invention will hereinafter appear and the invention is shown in one of its preferred embodiments in the accompanying drawings in which—

50 Figure 1 is an elevation partly in vertical section of the front end portion of a rock drill of the hammer type,

Figure 2 is a similar view with the machine turned at right angles to Figure 1, and

Figure 3 is a view similar to Figure 2 55 with the retainer swung to an inoperative position.

Referring to the drawings the front end portion of a hand held rock drill of the hammer type is shown for illustrative purposes having a cylinder A which is separated from the front head B by the front cylinder bushing C, and these parts are connected together by the usual spring pressed side bolts D. In this instance a working implement in the form of a drill steel E having a collar F is adapted to extend into the front head B for receiving the impact blows of the fluid actuated hammer piston of the machine.

A pair of trunnions G is preferably formed on the front head B on opposite sides thereof and is in this instance located in a plane offset from the central plane of the machine. Each trunnion is formed with a flattened portion H, which faces toward the outer end of the machine. A pair of side arms J is in this instance pivotally connected to the trunnions G and each arm is preferably formed with an opening K. A lug L on each side of the front head B serves as a stop for limiting the swinging movement of the side arms J beyond the operative position of the retainer.

In order to limit the outward movement 85 of the collar F on the steel E relative to the front head B, a yoke O is adapted to embrace the steel in such a manner that under normal working conditions the steel is permitted to move freely within the yoke 90 but cannot be entirely withdrawn from the front head B, because of the collar F. The yoke O is in this instance formed with a raised portion P against which the collar F is adapted to abut and a pair of arms Q is preferably connected to the yoke O on opposite sides thereof and extends substantially at right angles therefrom. The yoke arms Q are in this instance adapted to extend into the openings K of the side arms J, 95 and the ends R of the yoke arms Q are adapted to bear against the flattened portions H of the trunnions G.

In order to cushion the outward movement of the yoke O, a coil spring S in this instance surrounds each of the yoke arms Q in each of the openings K. One end of each coil spring S is adapted to bear against

one end of the opening K and the other end preferably bears against a nut T which is screwed onto one end of the yoke arms Q. The nuts T are in this instance provided 5 with holes U to enable a suitable tool to be inserted therein for screwing or unscrewing the nuts for adjusting the tension of the springs S. The springs S are preferably formed with projections V on each end 10 thereof, which are adapted to cooperate with recesses W in the side arms J and the nuts T to lock the nuts T in the desired position 15 of adjustment.

In the position of the retainer shown in 15 Figures 1 and 2, the yoke O is held in operative retaining position about the drill steel E to prevent withdrawal of the steel E. The end portions R of the yoke arms Q are held against the flattened portions H of the trunnions G by means of the springs S and in 20 this manner the yoke O is securely held in retaining position, so that the ordinary jars and shocks set up in the operation of the machine will not move the yoke from this 25 position.

As shown in Figure 3, the yoke O may be swung away from the steel E to enable the steel to be withdrawn from the front head B and the springs S will force the ends R of 30 the yoke arms Q against the trunnions G in order to hold the retainer in its inoperative position.

I claim:

1. A retainer for fluid actuated percussive machines comprising the combination with 35 the front end portion of a machine of a collared working implement adapted to extend into said front end portion, trunnions on opposite sides of said front end portion 40 having a flattened portion, said trunnions being in a plane offset from the central plane of the machine, side arms pivotally connected to said trunnions, a yoke adapted to embrace said implement, arms connected to 45 said yoke at opposite sides thereof and extending at substantially right angles therefrom, and spring means for cushioning the outward movement of said yoke adapted to force one end of said yoke arms against the 50 flattened portions on said trunnions to hold said yoke in operative retaining position.

2. A retainer for fluid actuated percussive machines comprising the combination with 55 the front end portion of a machine, of a collared working implement adapted to extend into said front end portion, trunnions on opposite sides of said front end portion having a flattened portion, said trunnions being in a plane offset from the 60 central plane of the machine, side arms

pivots connected to said trunnions, a yoke adapted to embrace said implement, arms connected to said yoke at opposite sides thereof and extending at substantially right angles therefrom into said side arms, 65 spring means for cushioning the outward movement of said yoke and adapted to force one end of said yoke arms against the flattened portions on said trunnions to hold said yoke in retaining position and means 70 for adjusting the tension of said spring means.

3. A retainer for fluid actuated percussive machines comprising the combination with 75 the front end portion of a machine, of a collared working implement adapted to extend into said front end portion, trunnions on opposite sides of said front end portion having a flattened portion, said trunnions being in a plane offset from the 80 central plane of the machine, side arms pivotally connected to said trunnions, a yoke adapted to embrace said implement, arms connected to said yoke at opposite 85 ends thereof and extending at substantially right angles therefrom into said side arms, a coil spring on each of said arms for cushioning the outward movement of said yoke and adapted to force one end of said yoke arms against the flattened portions on said 90 trunnions to hold said yoke in retaining position, and means on said yoke for manually adjusting the tension of said springs.

4. A retainer for fluid actuated percussive machines comprising the combination with 95 the front end portion of a machine, of a collared working implement adapted to extend into said front end portion, trunnions on opposite sides of said front end portion, said trunnions being in a plane offset from 100 the central plane of the machine, side arms pivotally connected to said trunnions and formed with an opening, a yoke adapted to embrace said implement for limiting the outward movement of the collar on said implement, arms connected to said yoke at opposite sides thereof and extending at substantially right angles therefrom into said opening, a nut screwed onto each of said yoke arms, and a spring on each of said yoke 110 arms adapted to cushion the outward movement of said yoke and to force one end of said yoke arms against the flattened portion on said trunnions to hold said yoke in operative retaining position, said yoke being adapted to be swung away from said implement and held in inoperative position. In testimony whereof I have signed this specification.

RUSSELL H. WILHELM.
